(57) **CLAIM**

The ornamental design for a rehydrator/inoculator device, as shown and described.

DESCRIPTION

FIG. 1 is a top perspective view of a rehydrator/inoculator device, showing our new design;

FIG. 2 is a bottom perspective view of the rehydrator/inoculator device of FIG. 1;

FIG. 3 is a front elevational view of the rehydrator/inoculator device of FIG. 1;

FIG. 4 is a rear elevational view of the rehydrator/inoculator device of FIG. 1;

FIG. 5 is a right side elevational view of the rehydrator/inoculator device of FIG. 1;

FIG. 6 is a left side elevational view of the rehydrator/inoculator device of FIG. 1;

FIG. 7 is a top plan view of the rehydrator/inoculator device of FIG. 1; and,

FIG. 8 is a bottom plan view of the rehydrator/inoculator device of FIG. 1.

The broken lines in the drawings are included for purposes of illustrating portions of the rehydrator/inoculator device that form no part of the claimed design.
